COMBINED FILTER AND MANIFOLD FOR INTERNAL-COMBUSTION ENGINES

Harold R. Sobeck, Novelty, Ohio, assignor to Air-Maze Corporation, Cleveland, Ohio, a corporation of Delaware

Application May 7, 1953, Serial No. 24,900

Term of patent 14 years

(Cl. D77—1)

To all whom it may concern:

Be it known that I, Harold R. Sobeck, a citizen of the United States residing at Novelty, county of Geauga and State of Ohio, have invented a new, original, and ornamental Design for a Combined Filter and Manifold for Internal Combustion Engines, of which the following is a specification, reference being had to the accompanying drawing, forming a part hereof.

Fig. 1 is a perspective view showing one end and a rear side of a combined filter and manifold for internal combustion engines, embodying my new design; and

Fig. 2 is a perspective view showing the other end and the front side of the same.

I claim:

The ornamental design for a combined filter and manifold for internal combustion engines, as shown.

HAROLD R. SOBECK.
